Electric & Manufacturing Company, East Pitts-
burgh, Pa., a corporation of Pennsylvania

Application May 25, 1937, Serial No. 144,754

13 Claims. (Cl. 175—354)

Our invention relates to electric discharge apparatus and has particular relation to electric discharge devices of the type incorporating an ignition electrode.

5 The discharge device to which our invention particularly relates in general comprises a cathode composed of mercury, lead, cadmium, or some other suitable metal, an anode to cooperate with the cathode and an ignition electrode associated with the cathode. When a current is transmitted between the ignition electrode and the cathode, a discharge is initiated between the anode and the cathode.

10 In the following discussion and in the claims, we shall refer to an "electrode of the mercury pool type". This expression shall be taken to include not only a cathode composed of mercury, but also cathodes of other suitable materials which function in substantially the same manner as mercury.

15 The ignition electrode associated with the cathode may be disposed either within or without the container in which the anode and cathode are located. If it is within the container its tip may be a short distance from the cathode so that during the ignition period a spark is produced between the ignition electrode and the cathode, or it may be in contact with the cathode. In the latter case, the ignition electrode is composed of a highly resistant material, such as silicon carbide, boron carbide, silicon, boron, or a number of other suitable materials, and to initiate a discharge, a current is transmitted through the ignition electrode and the electrode in contact therewith.

20 When we refer herein to an "ignition electrode", we mean thereby an ignition electrode of any general type including those located within or without the container that do not make contact with the cathode as well as those that do make contact with the cathode. An ignition electrode of the latter type we shall specifically designate herein as an "electrode of the silicon carbide type".

25 We have found that when the discharge device incorporates an ignition electrode of the silicon carbide type, a cathode spot will be formed upon the mercury cathode by sending suitable current through the ignition electrode, and the cathode spot serves to initiate a discharge between the anode and cathode. As an outgrowth of this discovery, a discharge device has been developed in which the anode is opposite and close to the cathode.

30 When current is transmitted between the ignition electrode and the cathode of a discharge device of this type, a spot is formed on the surface

of the cathode, and the discharge is transmitted between the spot and the anode. As the discharge passes the spot spreads and forms a number of spots all of which are located in the region of the ignition electrode. We have found an 5 arrangement of this type to operate satisfactorily for load requirements of moderate magnitude for currents less than 1000 amperes, for example. However, where the current drawn by the load is very large, the region of the spots on the surface 10 of the cathode since it is comparatively small becomes excessively heated, and the excessive vapor produced during the non-arching period results in backfires and other difficulties. This difficulty, while principally arising in discharge 15 devices in which the ignition electrode is of the silicon carbide type, is, of course, also involved although to a lesser extent, in discharge devices of other types.

It is accordingly an object of our invention to 20 provide a discharge device particularly adapted for the transmission of high currents of the order of 1000 amperes or more, wherein the cathode shall not become excessively heated.

Another object of our invention is to provide an 25 arc discharge device particularly adapted to the transformation or control of high currents.

More specifically stated, it is an object of our invention to provide a discharge device of the type having an ignition electrode that shall transform 30 or control heavy currents without difficulty.

In accordance with our invention, we provide a discharge device in which the single ignition electrode is replaced by a plurality of such electrodes so that for heavy currents a plurality of spot 35 regions are formed on the surface of the cathode. The ignition electrodes are supplied in parallel from a suitable source. On the application of potential to the ignition electrodes simultaneously one of the electrodes will in general effect the 40 striking of an arc before the others. If the ignition electrodes are merely connected directly in parallel, the potential drop between the other ignition electrodes and the cathode will be reduced 45 when this occurs. To make certain that the other ignition electrodes continue to operate, we provide coupling means, preferably coupling coils, between the ignition electrodes which when one of the electrodes has become effective, operate to impress an additional potential on the other electrodes so that they also become effective. To prevent the striking of an arc between the spot formed by one ignition electrode and the top or 50 head of another ignition electrode (as anode), 55

barriers are inserted between the ignition electrodes.

The novel features that we consider characteristic of our invention are set forth with particularity in the appended claims. The invention itself, however, both as to its organization and its method of operation, together with additional objects and advantages thereof, will best be understood from the following description of specific embodiments when read in connection with the accompanying drawing, in which:

Figure 1 is a diagrammatic view showing an embodiment of our invention;

Fig. 2 is a diagrammatic view showing a modification of our invention;

Fig. 3 is a diagrammatic view showing a further modification of our invention; and

Fig. 4 is a view in section showing a discharge device constructed in accordance with our invention.

The apparatus shown in Fig. 1 comprises a flat rectifier 5. The rectifier 5 consists of an evacuated container 7 having an insulating cylindrical wall 9 to the upper and lower edges of which metallic discs 11 and 13 are sealed and thus form the bases of a hollow cylinder. A mercury pool 15 is disposed in the bottom of the container and forms the cathode of the rectifier 5, while the upper disc 11 forms the anode.

In the upper disc 11, a pair of small openings are provided into which insulating plugs 17 and 19 of circular section carrying ignition electrodes 21 and 23 of the silicon carbide type are sealed. When the plugs 17 and 19 are in place, the ignition electrodes 21 and 23 dip into the mercury 15. So that the ignition electrodes shall operate independently of each other in initiating discharges and forming spot regions on the surface of the mercury, an insulating barrier 25 is provided which extends from the lower base 13 to a point a short distance from the anode 11. The barrier 25 is equipped with a small opening 27 through which the mercury may flow from one side thereof to the other.

While the flat rectifier 5 described herein has general applicability, it is shown as utilized to supply half-wave direct current from an alternating source 29. The load 31 to be supplied is connected between one terminal of the secondary 33 of a supply transformer 35 and the anode 11. The other terminal of the secondary 33 is connected directly to the cathode 15 through the lower base 13. The ignition electrodes 21 and 23 are supplied in parallel from a separate source 37 through a suitable transformer 39, the secondary 41 of which is connected to the primary 43 of a saturable transformer 45. The secondary 47 of the saturable transformer 45 is connected to the mid-tap 49 of a balance transformer 51 through an auxiliary rectifier 53 on the one hand and to the cathode 15 of the flat rectifier 5 on the other hand. The terminal taps 55 and 57 of the balance transformer 51 are connected to the ignition electrodes 21 and 23.

The source 31, whereby the ignition electrodes 21 and 23 are supplied may be of any general type and may have any general frequency. However, in the specific embodiment described herein, this source is of the same frequency as the main source 29, but its phase relative to the main source is adjustable.

When the circuit is connected, as shown in Fig. 1, and power is supplied to the saturable transformer 45, peak potential impulses having a polarity such that the ignition electrodes 21 and

23 are positive and the cathode 15 is negative are transmitted through the auxiliary rectifier 53. The impulses are impressed between the ignition electrodes and the cathode 15, and current flows between these electrodes and the cathode. In general, an arc is ignited first between the anode 11 and the portion of the mercury 15 associated with one or the other of the ignition electrodes 21 or 23. On the striking of this arc, an additional potential is impressed between the other ignition electrode and the mercury, and the latter continues to operate in spite of the fact that an arc has been struck first in the region of the former electrode. Immediately after the striking of an arc at the first ignition electrode 21 or 23, an arc is, therefore, also struck at the second electrode. The discharge device now continues to operate with two spot regions and to supply rectified current.

The transmission of current through the ignition electrodes 21 and 23 results in the initiation of discharges between the anode and the regions of the cathode associated with both electrodes within a very short interval of time. Accordingly, the potential impulse transmitted through the auxiliary rectifier 53 may be of short duration. However, where some time lag is involved, the wave form of the impulse may be broadened by properly selecting the dimensions of the saturable transformer 45.

It is to be noted, moreover, that while our invention is shown in the Fig. 1 embodiment as applied to supply half-wave current to a load, it may equally as well be applied for full-wave rectification and for inversion or conversion of any general character. The number of discharge devices or sets of anodes, cathodes and ignition electrodes will depend on the particular requirements of each case.

In the modification shown in Fig. 2, our invention is shown as applied to a system in which the load is so large that two ignition electrodes do not provide satisfactory operation. In the modification shown in Fig. 2, a discharge device 59 equipped with three ignition electrodes 61, 63 and 65 is utilized. Here again the electrodes 61, 63 and 65 are carried by insulating plugs 67, 69 and 71 which are inserted in the anode 11 in such manner that the electrodes dip in the cathode 15. In lieu of a single barrier, two barriers 73 and 75 are now provided between the central ignition electrode 63 and the other two, 61 and 65.

The three ignition electrodes 61, 63 and 65 are now again supplied in parallel, but the balance transformer 51 is now replaced by three pairs 55 of balance coils 77, 79 and 81. One coil 83, 85 or 87 of each pair is in series with a corresponding ignition electrode 61, 63 or 65. The remaining coils 89, 91 and 93 of the pairs are connected in series with each other. The individual coils 83, 85 and 89, 91 and 93, and 87 and 93 are in inductive relation with each other, and on the striking of an arc in the region of any one of the ignition electrodes 61, 63 or 65, current flows through the corresponding series connected coil 83, 85 or 87 and a potential is induced in the other coil 89, 91 or 93 of the pair. The induced potential causes current to flow through all of the coils 89, 91 and 93 connected in series with each other and the necessary additional potentials are induced in the coils 83, 85 or 87 connected in series with the ignition electrodes 61, 63 or 65 in the region of which an arc is not struck at first.

The modification shown in Fig. 3 is particularly

adapted for use in a system in which the load requirements are variable over a wide range. When light loads are supplied, it is undesirable that more than one ignition electrode should operate. Accordingly, we provide a relay 95, the exciting coil 97 of which is connected in the load circuit. When the load current is low, the relay 95 is deenergized and maintains the supply circuit of one of the ignition electrodes, say 23, open. When the load rises above a predetermined value, the relay 95 is operated and the supply circuit of the ignition electrode 23 is closed so that the two electrodes 21 and 23 operate in parallel as in the modification shown in Fig. 1. The modification shown in Fig. 3 is as applicable to a system incorporating a discharge device with more than two ignition electrodes as 59, for example, as it is to a system incorporating a discharge device such as 5.

In Fig. 4, a discharge device 99 particularly adapted for the practice of our invention is shown. The device comprises a container having an insulating cylindrical wall 101 which may be composed of a ceramic material or such a material as glass. The upper edge of the wall 101 is secured to the flange 103 of a flanged circular metallic disc 105 which may function as an anode. To the lower edge a flange 107 of a flanged cup-shape metallic element 109 is secured. The cup-shaped element 109 carries the liquid mercury 15, forming the cathode of the discharge device. The ignition electrodes 111 and 113 are carried by lead-in wires 115 and 117, which in turn are sealed through the cylindrical wall 101. A barrier 119 is supported along the center of the cathode cup 109 and extends upwardly into a groove 121 cut into the anode disc 105. It is provided with the customary opening 123 through which the mercury 15 may flow from one side to the other.

It is to be noted that while the multiple spot region discharge device is generally highly evacuated, it may also be filled with an inert gas at a low pressure or even at a pressure of several atmospheres.

Although we have shown and described certain specific embodiments of our invention, we are fully aware that many modifications are possible. Our invention, therefore, is not to be restricted except insofar as is necessitated by the prior art and by the spirit of the appended claims.

We claim as our invention:

1. A discharge device comprising an electrode of the mercury pool type, another electrode to cooperate with said mercury pool electrode, and means for producing a plurality of emissive spot regions on the surface of said mercury pool electrode, said other electrode being so arranged with respect to said emissive regions as to cause discharges to pass simultaneously between said plurality of spot regions and said other electrode.
2. A discharge device comprising an electrode of the mercury pool type, another electrode to cooperate with said mercury pool electrode, and a plurality of ignition electrodes associated with spaced regions of the surface of said mercury pool electrode, said other electrode being so arranged with respect to said spaced regions as to cause discharges to pass simultaneously between said spaced regions and said other electrode.
3. A discharge device comprising an electrode of the mercury pool type, another electrode to cooperate with said mercury pool electrode, and a plurality of ignition electrodes of the silicon carbide type in contact with spaced regions of the surface of said mercury pool electrode.

4. A discharge device comprising an electrode of the mercury pool type, another electrode to cooperate with said mercury pool electrode, a plurality of ignition electrodes of the silicon carbide type in contact with spaced regions of the surface of said mercury pool electrode, and barriers extending between said mercury pool electrode and said other electrode for separating said spaced regions.

5. In combination, a discharge device comprising an electrode of the mercury pool type, another electrode to cooperate with said mercury pool electrode, a plurality of ignition electrodes associated with spaced regions of the surface of said mercury pool electrode, and coupling means between said ignition electrodes which, when current flows between one of said ignition electrodes and said mercury pool electrode, operates to increase the potential difference between the other ignition electrodes and the mercury pool electrode.

6. In combination, a discharge device comprising an electrode of the mercury pool type, another electrode to cooperate with said mercury pool electrode, a plurality of ignition electrodes of the silicon carbide type in contact with spaced regions of the surface of said mercury pool electrode, and coupling means between said ignition electrodes which, when current flows between one of said ignition electrodes and said mercury pool electrode, operates to increase the potential difference between the other ignition electrodes and the mercury pool electrode.

7. In combination, a discharge device comprising an electrode of the mercury pool type, another electrode to cooperate with said mercury pool electrode, a plurality of ignition electrodes of the silicon carbide type in contact with spaced regions of the surface of said mercury pool electrode, barriers extending between said mercury pool electrode and said other electrode for separating said spaced regions, and coupling means between said ignition electrodes, which, when current flows between one of said ignition electrodes and said mercury pool electrode, operates to increase the potential difference between the other ignition electrodes and the mercury pool electrode.

8. In combination, a discharge device comprising an electrode of the mercury pool type, another electrode to cooperate with said mercury pool electrode and means for producing a plurality of emissive spot regions on the surface of said mercury pool electrode, and means for preventing the formation of one of said spots so long as the discharge current between said mercury pool electrode and said other electrode is below a predetermined value.

9. In combination, a discharge device comprising an electrode of the mercury pool type, another electrode to cooperate with said mercury pool electrode, and a plurality of ignition electrodes associated with spaced regions of the surface of said mercury pool electrode, and means for impressing potential simultaneously on said ignition electrodes to produce current flow between said ignition electrodes and said mercury pool electrode, said other electrode being so disposed relative to said spaced regions that a discharge passes to it from all said spaced regions when said current flow takes place.

10. In combination, a discharge device comprising an electrode of the mercury pool type, another electrode to cooperate with said mercury pool electrode, and a plurality of ignition electrodes associated with spaced regions of the sur-

face of said mercury pool electrode, means for impressing a periodically pulsating potential between said other electrode and said mercury pool electrode, and means for impressing potential pulses having a substantial value only for a time interval that is short compared to the period of said pulsating potential simultaneously on said ignition electrodes to produce current flow between said ignition electrodes and said mercury pool electrode.

11. In combination, a discharge device comprising an electrode of the mercury pool type, another electrode to cooperate with said mercury pool electrode, and a plurality of ignition electrodes associated with spaced regions of the surface of said mercury pool electrode, means for impressing potential of peaked wave form simultaneously on said ignition electrodes to produce current flow between said ignition electrodes and said mercury pool electrode, and coupling means between said ignition electrodes, which, when current is transmitted between one of said ignition electrodes and said mercury pool electrodes, operates to increase the potential between the other ignition electrodes and said mercury pool electrode.

12. In combination, a discharge device comprising an electrode of the mercury pool type, another electrode to cooperate with said mer-

cury pool electrode, and a plurality of ignition electrodes associated with spaced regions of the surface of said mercury pool electrode, and means for impressing potential simultaneously on said ignition electrodes to produce simultaneous current flow between said ignition electrodes and said mercury pool electrode, said other electrode being so disposed relative to said spaced regions that a discharge passes between all said spaced regions and said other electrode when said current flow is produced.

13. In combination, a discharge device comprising an electrode of the mercury pool type, another electrode to cooperate with said mercury pool electrode, and a plurality of ignition electrodes associated with spaced regions of the surface of said mercury pool electrode, means for impressing a periodically pulsating potential between said other electrode and said mercury pool, and means for impressing potential pulses having a substantial value only during a time interval that is short compared to the period of said pulsating potential simultaneously on said ignition electrodes to produce simultaneous current flow between said ignition electrodes and said mercury pool electrode.
